Primary Examiner — Kevin K Rudzinski*Assistant Examiner* — Clare Ann Gannon(74) *Attorney, Agent, or Firm* — AdamsIP, LLC; J. Hunter Adams(57) **CLAIM**

The ornamental design for a garter, as shown and described.

DESCRIPTION

FIG. 1 is a front perspective view of a garter showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detail view of the area 8 in FIG. 1; and, FIG. 9 is an enlarged detail view of the area 9 in FIG. 1. The dashed broken lines in the figures show portions of the garter that form no part of the claimed design. The dot-dash broken lines in the figures show boundaries that form no part of the claimed design. The shade lines in the figures show contour and not surface ornamentation.

1 Claim, 4 Drawing Sheets(56)
